United States Patent

Des. 239,072
Patented Mar. 9, 1976

239,072

SUPPORT STAND FOR A BLANKET

John F. Adams, 55 Lee Road,
Chestnut Hill, Mass. 02167

Filed Dec. 4, 1974, Ser. No. 529,683

Term of patent 14 years

Int. Cl. D6—99

U.S. Cl. D6—85

Fig. 2.

Fig. 3.

FIG. 1 is a perspective view of a support stand for a blanket showing the design;

FIG. 2 is a side elevational view thereof;

FIG. 3 is a front elevational view thereof;

FIG. 4 is a top plan view thereof; and

FIG. 5 is a bottom plan view thereof.

I claim:

The ornamental design for a support stand for a blanket, as shown.
